[57] CLAIM

The ornamental design for a container body for liquids
and the like, as shown and described.

DESCRIPTION

FIG. 1 is a front elevational view of a container body
for liquids and the like embodying our new design;
FIG. 2 is a side elevational view looking from the right
of FIG. 1; and
FIG. 3 is a top plan view thereof.
Broken lines showing the neck finish are for the purpose
of illustrating the environment of use.

FIG. 1

FIG. 2

FIG. 3
